UNITED STATES PATENT OFFICE.

FREDERICK C. MILLER, OF HILLSBORO, OREGON.

FOLDING OAR-LOCK.

1,171,060.

Specification of Letters Patent.

Patented Feb. 8, 1916.

Application filed May 18, 1915. Serial No. 28,922.

To all whom it may concern:

Be it known that I, FREDERICK C. MILLER, a citizen of the United States, residing at Hillsboro, in the county of Washington and State of Oregon, have invented certain new and useful Improvements in Folding Oar- Locks, of which the following is a specification, reference being had therein to the accompanying drawing.

10 This invention relates to a folding oar lock and has for its principal object the production of an efficient oar lock which may be quickly moved to a set-up position so as to receive an oar and easily move with 15 the swing of the oar but which may be easily moved to a folded position so as to be positioned out of the way when not in use.

Another object of this invention is the 20 production of a folding oar lock which is so formed as to allow the lock member to be swung downwardly upon the body portion of the device and remain in a socket thereby preventing the accidental displacement of 25 the lock member when the same is not in use.

A still further object of this invention is the production of a folding oar lock in 30 which the sleeve is rotatably or pivotally mounted so as to easily swing with the movement of the lock member, this lock member being slidably mounted upon a sleeve so as to be capable of being lifted and then swung downwardly so as to rest 35 upon the body portion of the device.

With these and other objects in view, this 40 invention consists of certain novel combinations, constructions, and arrangements of parts as will be hereinafter fully described and claimed.

In the accompanying drawings: Figure 1 is a detailed perspective view of a boat, showing a plurality of the oar locks, as constructed in accordance with this invention, 45 carried thereby. Fig. 2 is a central longitudinal section through the folding oar lock, showing the same in a set-up position. Fig. 3 is a central longitudinal section through the device when the same is assembled, showing the lock member swung 50 downwardly so as to rest upon the body portion of the device. Fig. 4 is a section taken on the line 4-4 of Fig. 3, looking in the direction of the arrows. Fig. 5 is a top plan view of the invention, the lock member being removed. Fig. 6 is a detailed 55

perspective view of the sleeve. Fig. 7 is an elevation of the lock member. Fig. 8 is a transverse section through the sleeve and lock member, illustrating the manner in 60 which the sleeve and lock member are held in engagement with each other.

Referring to the accompanying drawings by numerals it will be seen that the device comprises a body as indicated in general by 65 1. This body comprises the top 2 having the curved side walls 3 terminating in the flat base portion 4 in which there are formed the openings 5. This body is adapted to be placed upon the upper side portions of a boat 6 so as to allow suitable securing means to be passed through the openings 5 for fixedly retaining the body in position. This body has an enlarged thickened lock 7 formed integral upon the inner 70 portions of the top 2 and the side walls 3 as shown in Figs. 2, 3, and 4. A vertical opening 8 is formed so as to extend through the thickened portion 7 and communicate with the outer portions of the body 1.

The sleeve which is used in connection with this device is indicated by the numeral 75 9 and this sleeve has a pin 10 extending transversely through its lower portions as shown in Fig. 3. This pin 10 is adapted to

80 bear upon the lower surface of the thickened portion 7 for preventing the accidental displacement of the sleeve 9. This sleeve 9 has an enlarged shoulder 11 formed integral upon its upper end and since this shoulder 90 11 has a flat lower surface 12 it will bear evenly upon the upper portions of the top 2. Therefore, the sleeve 9 may freely rotate within the vertical opening 8 as desired but since the shoulder 11 bears upon the outer portions of the top 2 and the pin 10 will bear upon the lower portion of the thickened portion 7, it will be impossible to accidentally remove or displace the sleeve after the device has been assembled. 100 The sleeve 9 is also provided with a pair of aligned slots 13 extending longitudinally and with a notched portion 14 interposed between the slots 13.

The lock member comprises a yoke portion 15 formed integral upon the shank 16 while the bearing shoulder 17 is formed intermediate the yoke 15 and the shank 16. This shank 16 is solid and is adapted to fit within the sleeve 9. When the device is 110 assembled the pin 18 may be passed through the lower end of the shank so as to project

beyond the side portions thereof and fit within the alined slots 13 formed in the sleeve 9. Therefore, it will be seen that the shank may extend downwardly through the 5 sleeve 9 so as to allow the shoulder 17 to bear upon the upper portions of the shoulder 11 formed upon the sleeve. When the oar is passed through the yoke 15 of the lock member and is actuated in the usual manner for rowing a boat, the pin 18 will cause the sleeve 9 to pivot within the vertical opening 8 formed in the thickened portion 7. When the device is not in use however, the lock member may be lifted at which time 10 the pin 18 will ride within the slots 13 and when reaching the upper portions of the sleeves the upward movement of the lock member will be limited. At this time the lock member may be swung downwardly 15 through the notched portion 14 formed in the side portion of the sleeve.

The top 2 of the body 1 is provided with a curved groove 19 communicating with the channel 20 by means of the pocket 21. It 20 will be seen that the shape of the channel 20, the pocket 21, and the curved groove 19 constitute a socket portion in the upper portions of the body 1 which will conform in shape to the lock member and therefore 25 when the lock member is swung downwardly so as to rest upon the upper portions of the body 1 it will fit snugly within the socket formed by the channel, pocket, and groove and will be prevented from being 30 accidentally displaced. Therefore, when the device is not in use, the lock member will be retained in its correct position upon the upper portions of the body 1 without danger of slipping or accidentally moving from the 35 upper portions of the body. If it is so desired, when the lock member is swung to a set-up position, the sleeve may be swung or pivoted one-half of a revolution so as to allow a portion of the shoulder 11 to overhang the end of the channel 20 communicating with the vertical opening 8 and will thereby relieve considerable strain upon the shank 16 owing to the fact that the sleeve 40 will engage the shank at a higher point than it would if the notched portion 14 were allowed to remain in registry with the channel 20 and at the same time it will be seen that by having the channel portion closed in this manner even though the lock is lifted 45 until the pin 18 reaches the upper portion of the slots 13, it will be impossible for the lock member to be swung downwardly inasmuch as the notched portion will not register with the channel portion which will 50 allow the lock member to pivot.

From the foregoing description it will be seen that the lock member may be retained in a compact folded position when not in operation but it may be easily swung to a 55 set-up position so as to positively retain an

oar in its correct position to be actuated, this lock member being so supported as to easily swing with the movement of the oar.

What I claim is:

1. In a device of the class described the 70 combination of a body, a sleeve rotatably carried by said body, a lock member slidably mounted upon said sleeve, said lock member being adapted to receive an oar so as to retain the same in its correct position 75 when in operation, whereby when the oar is actuated it will impart a pivotal movement to said sleeve by means of said lock member, said lock member being capable of being lifted and then swung so as to rest upon 80 the upper portions of said body when not in use.

2. In a device of the class described the combination of a body, said body provided with a vertical opening, said body being 85 adapted to be supported upon the side portions of a boat, a sleeve rotatably mounted within said vertical opening, said sleeve provided with an enlarged shoulder formed upon its upper end so as to engage the 90 outer portions of said body, a pin passing through the lower end of said sleeve so as to engage the inner portions of said body thereby retaining said sleeve against accidental displacement, said sleeve provided with a pair of alined slots, a lock member carried upon said sleeve and provided with a shank positioned therein, a second pin extending through the lower end of said shank and extending through said slots, said lock 95 member being adapted to carry an oar, whereby upon the actuating of the oar said lock member will impart reciprocal rotary movement to said sleeve, said lock member being adapted to be lifted until the upward 100 movement thereof is limited by said second pin engaging the upper ends of said slots at which time said lock member may be swung downwardly so as to rest upon the upper portions of said body and be positioned in a compact manner when not in use.

3. In a device of the class described the combination of a body having a vertical opening, said body being adapted to be 115 carried upon the side portions of a boat, a sleeve rotatably mounted within said opening, means for preventing the accidental displacement of said sleeve, said sleeve provided with a notch formed in its upper side portion, a lock member carried by said sleeve and provided with a shank extending thereto, means carried by said shank and engaging said sleeve for preventing the displacement of said lock member, said lock member being adapted to be actuated by an oar extending therethrough whereby reciprocal rotary movement will be imparted to said sleeve, by said lock member when the same is operated, said lock member being 120 125 130

- capable of being lifted, means for limiting the upward movement of said lock member, said lock member being adapted to be swung downwardly through the notch formed in said sleeve so as to rest upon the upper portions of said body when not in use.
4. In a device of the class described, the combination of a body, said body having a vertical opening formed therein, a sleeve rotatably mounted within said opening, a lock member positioned upon said sleeve and provided with a shank extending thereto, means for retaining said sleeve in engagement with said body, means for holding said lock member in engagement with said sleeve, said lock member being capable of swinging said sleeve when said lock member is actuated by an oar, said lock member being adapted to be lifted when not in operation and to be swung downwardly upon the upper portions of said body, and means for retaining said lock member in a central compact position upon said body when not in use.
- 25 5. In a device of the class described the combination of a body, said body provided with a vertical opening, a sleeve rotatably

carried within said opening, said sleeve provided with a notched portion, means for retaining said sleeve in engagement with said body, a lock member carried upon said sleeve, said lock member provided with a shank extending thereto, means for retaining said lock member in engagement with said sleeve, said lock member being capable of sliding upon said sleeve whereby said lock member may be lifted when not in use and then swung downwardly through the notch formed in said sleeve so as to rest upon the upper portion of said body, said body provided with a socket formed upon its upper portion, said socket conforming in contour to the shape of said lock member whereby when said lock member rests upon the upper portion of said body it will fit snugly within said socket and will be retained in its correct central position upon the upper portions of said body.

In testimony whereof I hereunto affix my signature in presence of two witnesses.
